UNITED STATES PATENT OFFICE.

ALFRED A. GLIDDEN, OF WATERTOWN, AND LEONARD E. BEST, OF BOSTON, MASSACHUSETTS, ASSIGNEES TO HOOD RUBBER COMPANY, OF WATERTOWN, MASSACHUSETTS, A CORPORATION OF MASSACHUSETTS.

DESIGN FOR A RUBBER HEEL.

60,451.

Specification for Design. Patented Feb. 21, 1922.

Application filed May 25, 1921. Serial No. 472,602. Term of patent 3½ years.

To all whom it may concern:

Be it known that we, ALFRED A. GLIDDEN and LEONARD E. BEST, citizens of the United States, and residents of Watertown, in the County of Middlesex and State of Massachusetts, and Boston, in the County of Suffolk and State of Massachusetts, respectively, have invented a new, original, and ornamental Design for Rubber Heels, of which the following is a specification, ref-

erence being had to the accompanying drawing, forming a part thereof.

Figure 1 is a plan view of a rubber heel, showing our new design, and

Fig. 2 is a side view.

We claim:

The ornamental design for a rubber heel, as shown.

ALFRED A. GLIDDEN.
LEONARD E. BEST.
